[57] CLAIM

The ornamental design for a condiment shaker or similar article, substantially as shown and described.

DESCRIPTION

FIG. 1 is a side elevational view of a condiment shaker or similar article showing my new design, the other sides being a mirror image;

FIG. 2 is a top plan view thereof;

FIG. 3 is a vertical cross-sectional view thereof, taken along line 3—3 of FIG. 2; and

FIG. 4 is a bottom plan view thereof.

The broken lines showing of cap in FIGS. 1 and 3 are for illustrative purposes only.

FIG. 1.

FIG. 3.

FIG. 2.

FIG. 4.
